GAME APPARATUS.

1,143,210.

Specification of Letters Patent. Patented June 15, 1915.

Application filed September 26, 1914. Serial No. 863,606.

To all whom it may concern:

Be it known that I, GUSTAVE A. M. LILJENCRAANTZ, a citizen of the United States, residing at Chicago, in the county of Cook 5 and State of Illinois, have invented new and useful Improvements in Game Apparatus, of which the following is a full, clear, and exact description.

My invention relates to amusement devices 10 and particularly to games comprising a game-board, markers, and dice, which latter are thrown to indicate the position the markers shall occupy on the diagram mounted on said game-board.

15 The object of my invention is to provide a game in which the various incidents of political life, and public offices, to which politicians aspire and sometimes occupy, are used as stations to indicate the advancement 20 of the player toward the final goal, or position marked "President," the attaining of which wins the game. This I accomplish by a diagram consisting of a plurality of systematically arranged geometric or other 25 designs and pictorial indicia designating certain of said designs, and by other paraphernalia, substantially as hereinafter fully described, and as particularly pointed out in the claims.

30 In the drawings: Figure 1 is a plan view of a game-board on which the diagram constituting the principal feature of my invention is mounted. Fig. 2 is a detail view of one of the party emblems that may be used 35 in connection with my improved game. Fig. 3 is a perspective view of a marker used in connection with the same. Fig. 4 is a similar view of a dice used therein.

The diagram mounted upon the game-board A, illustrated in the drawings, comprises two series of circles each consisting of an entrance circle a near the lower edge and fourteen horizontal rows of corresponding circles b, arranged in tiers one above the 45 other and so that the circles of one row will be in a staggered position to the next row or rows. Just above the upper row of circles is a terminal circle c, which is, preferably, greater in diameter than the remaining 50 circles of the series and indicates the goal the players strive for. The entrance circles a and the terminal circle c are, preferably, situated nearer the center of board A, and commencing with the entrance circles the circles of each series are connected by one or more lines that constitute the path

d, which the players of the game must follow during the progress of the same. As shown, this path connects the entrance circle with the circle at the inner end of the lowermost row of circles, each of which latter are connected by a horizontal path, and the circle at the end of the lowermost row opposite the entrance circle is connected to the circle at the outermost end of the second or 60 row next it, and the circles of this second row are connected by a horizontal path, and the circle at the end of the second row nearest the center of width of the game-board is connected with the circle of the corresponding 65 end of the third row, and so on to the terminal circle c. Commencing with the entrance circle and ending with the terminal circle these circles of each series are numbered "1" to "100," respectively. Each of 70 these series of circles are intended to indicate the advancement of the player in the political party of his choice, and each series is designated by a party emblem; thus, the right hand series of circles is designated by 75 the picture of an elephant B, representing the Republican party, which is placed below the inner end of the lowermost series of circles next the entrance-circle, and the left hand series of circles, which is devoted to 80 the player or players preferring to represent the Democratic party, by the picture of a donkey C, which is placed below the inner end of the lower row of circles next the entrance-circle thereof. 85

A certain number of the circles of each series are selected to designate certain civic positions to which those entering the arena of political life aspire, and certain incidents that have been known to happen to politicians during their advancement in the profession of politics and have more or less influence in the success of their careers. For instance, in the circles representing the Republican party, in the right hand series of 90 circles, the circle marked "7" is designated by the picture and the words (prefaced by numeral "7") as a "Letter Carrier." In like manner the circle numbered "12" is made to indicate the incident of being 95 "Found in Gambling Place." Circle "16" is similarly designated as Pound Master; circle "25" as a "State Senator"; circle "30" represents the incident "Accepting Bribes"; circle "34" indicates the "Office of Sheriff"; circle "43" "Postmaster"; circle "52"— 100 "County Judge"; circle "70"—"Congress— 105 " 110 man"; circle "80"—"U. S. Comptroller"; circle "90" "Sec'y. of the Interior"; circle "94"—"Postmaster Gen'l."; circle "96"—"Sec'y. of War"; circle "99"—"Vice-President"

5 After the words indicating the incident "Accepting Bribes" (circle 30) and the incident "Embezzlement", by which circle "48" is indicated, and the incident of "Bribing 70 Corporations", by which circle "85" is designated, and after the words describing said incidents the word "Trial" appears in parentheses. The circle "25" is designated in the manner hereinbefore described, by the 10 act described as "Letter Appointment 92", and this circle and all of the circles designating a civic office or any of the incidents hereinbefore illustrated are made more 15 conspicuous by giving them a double circular 20 border.

The left hand series of circles representing the Democratic party likewise have circles numbered "7"—"12"—"16"—"25"—"30"—"34"—"43"—"48"—"52"—"65"—"70"—"80"—"85"—"90"—"92"—"94"—"96"—"98" and "99" indicate by words and pictures in the manner shown and hereinbefore described, some civic office or some incident liable to occur during the advancement 25 of a politician, in substantially the same way as hereinbefore fully explained with reference to the right hand series of circles, and the terminal circles of each series (99 and 100, respectively) are designated 30 by the words "Vice-President" and "President" and by the word "Nomination". Between these two series of circles, preferably, near the upper portion thereof, is a picture of a chair surmounted by an 35 eagle with a scroll in its mouth and marked with the words "Elected President", and below this is a picture of an eagle in flight with a gavel in its claws designated by the words "Elected Vice-President", and circle 40 "60" of each series is made of some solid color, preferably black, and is designated by a horse of similar solid color and by the words "Dark Horse", preferably by the 45 numeral "60", substantially as shown.

50 Any ordinary game markers, such as shown in Fig. 3 of the drawings, may be used in the playing of my improved game and ordinary dice, similar to that shown in Fig. 4, are used by the players to determine their advancement. The game is played by any number of persons, each of whom selects to play in the series of circles representing the political party of his choice, and while it is preferable to have an even number of players representing each party, it is not necessary. The players, first of one party and then of the other, throw the dice, and advance to the circle the number of which corresponds to the total number of spots on the upper side of the dice so thrown. The next throw of the player advances him to the circle indicated by the number to which the throw of the dice entitles him, added to the number of the circle his marker last occupied, and so on. Should the throw of 70 the dice entitle him to move his marker to the circle designated by a civic office, he thereupon becomes possessed of said office and is known by the title thereof until he is entitled to place his marker on a higher 75 number designating a higher office, whereupon his title becomes changed, and he is known as by the title of the last mentioned office. If, during his advancement through the game, his marker becomes placed on a 80 circle indicating an incident that may affect his political career, which has the word ("Trial") following it, before advancing farther toward the goal of the game, the players of each side throw the dice and if 85 the number represented by the total throw of the side opposed to the side of the player who is to be tried, is greater than that of his side, said player is "guilty" and must begin the game over again, commencing at the 90 entrance-circle and advancing as before. If the side to which the player on trial belongs casts a total throw of the dice greater than the opposing side then said player is "not guilty", and continues to play the same as if 95 said incident had not been encountered. In this manner the players finally reach the end of the series of circles representing the side or political party to which he belongs, and he can only place his marker on the 100 circle "99", indicating "Vice-President" or the terminal circle "100", indicating "President" by a throw of dice the count of which equals the number intervening between that occupied by his marker and the 105 "Vice-President" circle or terminal, or the "President" circle. When the player's marker is upon these circles he is supposed to be in "nomination" and must then wait until the fate of the other players of the 110 game on his side have advanced as far as it is possible for them to do toward the terminal-circle.

When the nominations for "President" and "Vice-President" have been made by 115 the advancement of two players on each side, in the manner just described, to the terminal circles "100" and "99", respectively, the game continues, but the players in nomination for "President" cast their dice to obtain double sixes and the players in nomination for "Vice-President" cast their dice for double aces (ones), whereas the unsuccessful players—those who failed to be put in nomination, begin to play the circles representing the party of their choice over again and try to put their marker on the "Dark Horse" circle before the players in nomination are able to cast double sixes or double aces. If 120 double sixes or double aces are cast before 125 130 an unsuccessful player can, according to throw of the dice, place his marker on the "Dark Horse" circle, the player in nomination casting such doubles is elected to the office his marker may be on. If a player, not in nomination, should be able to place his marker on the "Dark Horse" circle before such doubles can be thrown, such player is declared elected to the Presidency and wins the game. If desired, one of these series of circles could be indicated by a "moose head," substantially as shown in Fig. 2, constituting the emblem of the "Progressive" party, or by the emblem or title of some other party, and the game played between the adherents of any two political parties, substantially in the manner hereinbefore set forth.

I do not wish to be confined to the exact number of circles or the particular arrangement of said circles of each series, as hereinbefore described and as illustrated in the drawings, nor do I wish to be confined to the use of circles to indicate stations upon which the markers of the players are placed, because it is obvious that the number of said circles or other designs could be decreased on increased and the arrangement thereof changed without departing from the spirit of my invention.

What I claim as new is:

1. In a game apparatus, a suitably mounted diagram representing several series of circles arranged in longitudinal groups, and the circles of each group being arranged in transverse rows and connected successively by suitable straight lines and numbered in numerical order, from one end to the other thereof, and the end circles of each transverse row being connected by suitable straight lines to the end circles of the preceding and succeeding rows, and certain selected circles including the last being suitably designated by the title of a civic office, and certain other selected intermediate circles of each of said series of circles being designated by a statement of some wrong or crime. 45

2. A game apparatus comprising a suitably mounted diagram representing several independent series of circles arranged in longitudinal groups, the circles of each group being arranged in horizontal rows, one above the other, and being successively connected by suitable lines and numbered in numerical order of their succession, certain 50 of the circles of each series including the last being designated by the titles of civic offices, and certain other circles by the names of crimes, and single circles located above 55 the longitudinal groups and each being connected to the inner circle of the top row of one of the groups, said single circles being designated by the title of a high office. 60

3. In a game apparatus, a suitably mounted diagram having a plurality of horizontal groups each being designated by the name of a political party and each consisting of corresponding parallel rows of circles arranged one above the other, and each series 65 designated by the proper party emblem, and the circles of each series being arranged in succession and connected by a line and numbered numerically in the order of their succession; certain of the circles of each series 70 including the last being designated by the titles of certain civic offices, and one of said circles being designated as a "dark horse," and a picture of a chair designated by the words "Elected President," being located 75 between the groups and constituting the winning point of the game. 80

In witness whereof I have hereunto set my hand this 23rd day of September, 1914.
